[57] CLAIM

The ornamental design for a grid light fixture, as shown and described.

DESCRIPTION

FIG. 1 is a top plan view of my design for a grid light fixture; FIG. 2 is a front elevational view of my design for a grid light fixture;

FIG. 3 is a bottom plan view of my design for a grid light fixture;

FIG. 4 is a side, elevational view of my design for a grid light fixture as evidenced from the left;

FIG. 5 is a side elevational view of my design for a grid light fixture as viewed from the right; and,

FIG. 6 is a partial cross sectional view of my design for a grid light fixture, the end cap being fragmentarily shown for purposes of disclosure.

The transparent tube is fragmentarily shown in FIGS. 1 and 2 for clarity of disclosure.
